COMBINED BALL GAME PADDLE AND
INDICATOR OR SIMILAR ARTICLE

James E. Gibson, Jr., High Point, N. C.

Application May 27, 1953, Serial No. 25,201

Term of patent 7 years

(Cl. D34—5)

To all whom it may concern:

Be it known that I, James E. Gibson, Jr., a citizen of the United States of America, residing at High Point, county of Guilford, and State of North Carolina, have invented a new, original and ornamental Design for a Combined Ball Game Paddle and Indicator or Similar Article, of which the following is a specification, reference being had to the accompanying drawing forming a part thereof.

Figure 1 is a plan view of a combined ball game paddle and indicator or similar article embodying my new design;

The ball tethering cord has been partly broken away in Figs. 2 and 3 for convenience of illustration.

The dominant features of my new design are shown in solid lines in the drawing.

I claim:

The ornamental design for a combined ball game paddle and indicator or similar article, as shown and described.
